UNITED STATES PATENT OFFICE

SAMUEL B. BOWMAN, OF ZANESVILLE, OHIO, ASSIGNOR TO HAZEL-ATLAS GLASS CO., OF WHEELING, WEST VIRGINIA, A CORPORATION OF WEST VIRGINIA

LEER

Application filed June 18, 1928. Serial No. 286,123.

In the annealing of glassware, it has been common practice for many years to employ continuous leers, the ware to be annealed being placed in the forward end of the leer, 5 and being annealed while the ware is being continuously carried toward the rear end of the leer. These leers may be sufficiently large to anneal the ware from several forming machines, or they may be of 10 a smaller type, sometimes termed individual leers, which are adapted to anneal the ware from a single forming machine, or sometimes the ware from two forming machines. The individual leer is sometimes more desirable 15 for use than the larger leers, because of the nature and location in the glass plant of the other units necessary for the production of glassware, such as the tanks, forming machines, packing room, etc. In addition, the 20 smaller leer may possess certain advantages, such as annealing more quickly, economizing fuel, etc. The larger leer usually requires the same amount of fuel, whether or not it is being used to capacity, while with 25 the smaller leers the number in use will vary with the production, thus avoiding the waste of fuel which results from operating large leers at less than capacity. In some instances, individual leers are better adapted than 30 large leers, in efficient and economical production. The present invention relates to the mechanical construction of, and detail improvements in a continuous individual leer, arranged in close relation to a 35 forming machine, so that the ware is fed directly from the forming machine to the leer, such as illustrated in the Brookfield Patent No. 836,297, granted November 20, 1906.

40 Referring to the drawings:

Figure 1 is a side elevational view of the forward portion of the leer; parts being broken away to show the interior construction.

45 Figure 2 is a side elevational view of the rear portion of the leer; being a continuation of Figure 1; and parts being broken away to show the interior construction.

50 Figure 3 is a vertical transverse sectional view taken on line 3—3 of Figure 1.

Figure 4 is a vertical transverse sectional view taken on line 4—4 of Figure 2.

Figure 5 is a detail end view of the battery of cooling pipes illustrated in side elevation in Figure 2.

55 Figure 6 is a perspective view of a portion of the leer; the heat insulation material within and above the frame being omitted, and a portion of the conveyer being also omitted, to more clearly show the 60 construction of the frame.

Figure 7 is a vertical longitudinal sectional view of the fire box; and

Figures 8 and 9 are detail views illustrating the means for guiding the movements of 65 expansion and contraction of the rails.

Numeral 1 refers generally to the leer, which is of the individual type, and is adapted to be arranged in close relation to the forming machine. The leer is preferably portable 70 in order that it may be easily arranged in the desired relation to a forming machine, or may be moved to various desired positions in the factory. It is the usual practice in glass factories to mount various machines on rollers, to facilitate their movement, and if desired the present leer may be provided with ordinary rollers such as shown in the patent to Denning No. 1,132,459, granted March 16, 1915; but I prefer to employ such rollers 75 only at the front of the leer; the rollers being indicated by numeral 2, and carried by brackets 3 attached to the leer frame. At suitable intervals rearward of these rollers, I provide horses 4, which carry at their upper ends 80 rollers 5, extending substantially the entire width of the leer. This results in a more substantial structure than the ordinary rollers, and yet provides means by which the leer may be easily adjusted into position with 85 relation to a forming machine, or be moved to different positions in the factory. In order that the leer may be vertically adjusted, the horses are preferably of the jack type; the vertical movement being effected by adjustment of the nuts 4' threaded on the rods 4".

90 The frame of the leer is extremely simple in construction, is relatively inexpensive in that it is made of standard stock material, such as plates; angle irons, channel irons, 100

straps, etc.; and the construction is so stand-
ardized, that leers of different width are made
by merely employing plates of different
width.

5 The bottom of the frame is formed of an
ordinary metal plate 6 which extends substan-
tially the full width and length of the leer;
and may of course, comprise a plurality of
10 plates riveted together. The side frames con-
sist of channel irons 7, one arranged along
each side edge of the bottom plate, extending
the full length thereof and riveted thereto.
At intervals throughout their lengths, the
15 upper portions of the channel irons, or side
frames, are rigidly connected together by
means of angle irons 8, the ends of which
are riveted to brackets 9, which brackets are
riveted to the channel irons or side frame.
Thus by the use of standard stock material,
20 a strong and durable leer frame is inexpen-
sively fabricated, and the construction is
standardized to such an extent that in the
manufacture of leers of different width, for
handling ware of materially different sizes,
25 it is only necessary to employ bottom plates
of different width.

Any desired means may be employed for
supplying the necessary heat to the leer, but
in the present form I employ an ordinary
30 fire-box 10, provided with baffles 10' and 10'',
which cause the flame and products of com-
bustion to follow a circuitous path before the
gases pass through the opening 10''' into the
leer. This fire-box is mounted in a frame
35 formed of angle irons 11 and reinforced by
straps 12; the unit being preferably remov-
ably attached to the side frames 7 by means
of brackets 13 which are riveted to the leer
side frames, and by bolts which pass through
40 these brackets and through plates 14; the low-
er ends of the plates 14 being riveted to the
angle iron frame of the fire-box. Short pieces
of angle iron, indicated by numeral 15, are
riveted to the front and rear of the fire-box
45 frame, and constitute abutments for jacking
up the fire-box when it is to be removed from
the leer. If desired, the fire-box may be pro-
tected by a sheet metal covering.

Numeral 16 indicates burners which lead
50 into the fire-box 10, and which are provided
with the usual valves 17. These burners are
used for heating up the leer when it is put
into operation, but after the leer has reached
the proper temperature the burners are
55 turned very low, or shut off entirely, depend-
ing on the character of ware being annealed.

In the form illustrated herein, I have
shown, more or less diagrammatically, a
cross-conveyer 19 mounted on the leer frame
60 at the front end thereof, and a shadow pan
20 spanning the space between the cross-con-
veyer and the leer conveyer. This cross-con-
veyer extends beyond one side of the leer into
cooperative position with a forming ma-
65 chine; but in other constructions of this same

leer, the ware is delivered from the forming
machine directly to the leer conveyer; and
it will therefore be understood that in such
installations the cross-conveyer 19 and shad-
ow pan 20 may be omitted.

70 There are many forms of conveyers for
glass leers disclosed in the prior art, such as
endless cables as illustrated in the patent to
Stender No. 818,573, granted April 24, 1906;
or endless chains, as illustrated in the patent
75 to Zellers et al. No. 573,318, granted December
15, 1896; or mesh conveyers, as illustrated
in the patents to Meyer No. 564,568, granted
July 21, 1896, or Calhoon et al. No. 574,389,
granted January 5, 1897; or roller convey-
80 ers, which are disclosed in various patents,
such as Heisey et al. No. 365,813, granted July
5, 1887, or Butler No. 679,292, granted July
30, 1901; or a conveyer comprising endless
chains carrying transversely extending per-
85 forated conveyer plates or leer pans, such as
shown in the patent to Rau No. 1,195,087,
granted August 15, 1916; or the type which
has been in general use for many years, which
is illustrated in many patents, and which
90 consists of endless chains carrying trans-
versely extending solid or imperforate plates
or leer pans. Although any of the well
known forms of conveyers for glass leers may
be employed in the present leer, I prefer the
95 same type of conveyer that has been commonly
used for many years in the large leers and
which is the type last described above.

Such conveyer comprises the endless chains
100 21 which extend over sprocket wheels at the
front and rear of the leer; the chains being
driven by a motor 22 which is operatively
connected with a sprocket wheel 23 on the
end of the shaft 24 which carries the sprocket-
105 chains engaging and driving the conveyer chains.
The motor and associated parts are carried
by a frame 25 suspended from the leer frame.
The ordinary belt tightener 26 is provided
for maintaining the conveyer chains under
proper tension. The leer pans, indicated by
110 numeral 27, are made of thin sheet metal and
are preferably provided with downturned
flanges; the pans extending transversely of
the leer and being attached to the endless
chains. These plates carry rollers 28 on their
115 under sides, and throughout the upper run
of the conveyer these rollers travel on rails
29, which are ordinary angle irons. I also
preferably provide a smaller angle iron 30,
120 which functions as a guard, and which is
welded to the upstanding flange of the rail
29, so that the horizontal flange of the angle
iron 30 will project slightly over the ends
of the leer pans, and thus act as a guard to
125 avoid the jamming of glass or other material
between the ends of the leer pans and the
side walls of the leer. This guard rail ex-
tends inwardly the desired distance from the
hot end of the leer.

130 The rails 29 extend substantially the full

length of the leir and are mounted on the transversely extending angle irons 8, and it will be understood of course, that each of these rails may be formed of a single piece, 5 or a plurality of pieces laid end to end, but suitably spaced to provide for expansion and contraction. The rails may be anchored at one end or at any point intermediate their ends, to one of the ties 8, by means of countersunk bolts. For the purpose of preventing the rails from being displaced or overturned, I provide clips 31 which are bolted to the angle irons 8 and which clamp over the horizontal flange of the angle iron 29 constituting the rail. Brackets 32 are also bolted 10 to the angle irons 8, and the upper ends of the brackets are provided with flanges 33 which clamp over the top of the vertical flange of the rail angle iron. For the purposes of maintaining the rails in proper alignment and permitting the necessary expansion and contraction, guide rollers 35 are mounted on the angle irons 8 on opposite sides of the rails and in rolling contact therewith, as clearly illustrated in Figs. 3, 8 and 9.

The lower or return run of the leir conveyor is supported by rollers 36 which are mounted in brackets 37 riveted to the bottom plate 6 of the leir. By reference to Fig. 6, 30 it will be noted that I preferably provide bearings 37' which are removably mounted on the brackets 37, and that the rollers 36 are removably mounted in these bearings.

The walls of the leir are made of suitable 35 heat insulating material 38; the walls being built up on the leir frame hereinbefore described, and being of the required thickness to insure proper heat insulation. In the form illustrated, the refractory construction is almost entirely exposed, and is reinforced by 40 means of straps 41 of flat stock, the lower ends of which are secured to the side frames of the leir, and the upper ends project over the angle iron 42 extending along the upper edges of the construction; the oppositely arranged 45 straps being connected at their upper ends by the rods 43, by means of which the straps are caused to tightly bind the refractory construction. In some instances I prefer to protect the refractory construction by a sheet metal covering.

The roof and side walls of insulating material which inclose the upper run of the conveyer do not extend the full length of the 50 conveyer, it being customary to leave a considerable length of the rear portion of the conveyer exposed, so that the ware may be properly cooled and ready for packing by the time it reaches the end of the conveyer. It 55 will be noted by reference to Figure 2 that the insulating walls and roof above the upper run of the conveyer terminate at the point indicated by numeral 44; but it will also be noted that the insulating side walls and floor 60 within the leir frame and surrounding the

conveyer, extend to the rear end of the frame and conveyer. Obviously, the extending of this insulation material to the end of the conveyer avoids considerable heat loss, which would occur if the rear portion of the conveyer were entirely exposed. 70

For the purpose of aiding in the control of the leir temperature, the roof of the leir is provided with a plurality of properly spaced flues 45; each flue having a damper 46. By 75 the operation of these dampers, the amount of heat carried off at any point in the leir may be regulated, thereby insuring a proper temperature throughout the leir. This arrangement of flues has been in use for many years, 80 and if desired they may lead to a common flue, which is also a conventional arrangement.

It has also been customary to arrange vertically adjustable curtains or baffles within the 85 leir, and such curtains or baffles are indicated in the present leir by numeral 47. These baffles are made of asbestos or metal, and may be vertically adjusted by any desired means. In the present form, the baffles are slidably 90 mounted between slightly spaced angle irons 48 which act as guides therefor; and a shaft 49 is rotatably mounted on the angle irons and is operatively connected with the upper end of the baffle by means of a chain or other 95 flexible member 50. The shaft is provided with a crank 51, by the rotation of which the baffle is raised or lowered to the desired position. These baffles are adjusted for different 100 heights of ware and they are usually positioned so that the ware will just clear them. This arrangement of baffles not only reduces air currents through the leir, but also tends to keep the heated gases down in contact with the ware being annealed. 105

When the annealed ware is carried out on the open conveyer from the interior of the leir, it is ordinarily subjected to considerable shock due to the sudden change in temperature; and this results in loss of ware due to 110 strains or fractures. This objectionable feature is eliminated in the present leir by means of a battery of cooling pipes 52, the rear ends of which open to the atmosphere, and the front ends of which are connected with a flue 115 53, having a damper 54. In operation, air from outside the leir will be drawn into these pipes and pass out through the flue; and the air thus continuously passing through these pipes will absorb the heat therefrom and produce the desired cooling effect in the leir, without the cold air coming into direct contact with the ware. Forced draft may be employed with these cooling pipes, if desired. 120

I find it desirable to vary the point at 125 which the annealed ware comes in contact with the atmospheric air; for even though ware may be perfectly annealed, yet it may be strained or fractured if it is brought out into the atmospheric air too early. In order 130

- that this point may be varied, I have provided a number of hoods 55 which are arranged end to end over the open conveyer. In the annealing of some ware these hoods 5 are not used at all; and in other cases several of them are employed; it being desirable to use as few as possible, so that the ware will come into contact with the cooling atmospheric air as early as practicable without injuriously affecting the annealed ware. In 10 the form disclosed herein, the hoods are telescopically arranged, so that the sections may be pushed in or pulled out sufficiently to give a hood of the desired length.
- 15 When the ware leaves the hoods it is exposed to the atmosphere for a few feet of travel, and then passes beneath a wind box 56, through which air is forced downward at a moderate pressure against the ware and 20 cools it, without danger of breakage. By reference to Fig. 2, it will be noted that the orifices 57 of the air jets are graduated in size, so as to gradually increase the amount of cooling air supplied to the ware.
- 25 From the foregoing description, it will be apparent that I have devised a leer of the individual type or smaller type, which is of extremely simple construction, is made largely of standard stock material, so that 30 it is relatively inexpensive in manufacture, and yet which is highly efficient in operation.
- Having fully described the invention, what I claim as new is:
1. A leer including a frame, said frame 35 formed of channel irons extending substantially the full length of the leer and constituting the leer side frames, a bottom plate attached to the channel irons, transversely extending angle irons rigidly connecting the 40 channel irons, and longitudinally extending angle irons mounted on the transverse angle irons and constituting rails for a leer conveyer.
2. A leer including a frame, said frame 45 formed of channel irons extending substantially the full length of the leer and constituting the leer side frames, a bottom plate attached to the channel irons, transversely extending angle irons rigidly connecting the 50 channel irons, longitudinally extending angle irons mounted on the transverse angle irons and constituting rails for a leer conveyer, and rollers for guiding the rails during expansion and contraction.
3. A leer including a frame, said frame 55 formed of channel irons extending substantially the full length of the leer and constituting the leer side frames, transversely 60 extending angle irons rigidly connecting the channel irons, longitudinally extending angle irons mounted on the transverse angle irons and constituting rails for a leer conveyer, and longitudinally extending angle 65 irons mounted on the vertical flange of the
- angle iron rails and constituting guards for the leer conveyer.
4. In a leer, a metallic frame extending the full length of the leer, an endless conveyer housed within said frame and extending substantially the full length thereof, a tunnel of heat insulation material extending over only a portion of the length of said conveyer, and telescopically arranged hoods positioned over said conveyer beyond the 70 tunnel.
5. In a leer, a metallic frame extending the full length of the leer, a conveyer housed within said frame and extending substantially the full length thereof, a tunnel of heat 75 insulation material extending over only a portion of the length of said conveyer, means over the conveyer and spaced rearwardly of the tunnel for applying cooling air to the ware, a hood construction arranged over the 80 conveyer and between the tunnel and said means, said hood construction being adjustable as to length, to vary the distance the top and sides of the ware are fully exposed to the atmosphere before being subjected to 85 the cooling air.
6. A leer including a tunnel, a conveyer extending through and beyond said tunnel, means spaced rearwardly from the tunnel for applying cooling air to the ware on the conveyer, and means for varying the distance through which the top and sides of the ware are fully exposed to the atmosphere before 90 reaching the first-mentioned means.
